UNITED STATES PATENT OFFICE.

ABRAHAM L. MARSHALL, OF KANSAS CITY, MISSOURI.

OIL-BURNER.

1,322,712.

Specification of Letters Patent. Patented Nov. 25, 1919.

Application filed January 20, 1919. Serial No. 271,985.

To all whom it may concern:

Be it known that I, ABRAHAM L. MARSHALL, a citizen of the United States, residing at Kansas City, in the county of Jackson, State of Missouri, have invented certain new and useful Improvements in Oil-Burners, of which the following is a full and exact specification.

The present invention relates to oil burners and aims to provide an improved burner construction adapted for efficient operation on petroleum oils of ordinary quality.

Accordingly one of the objects of the invention is to devise a burner structure in which the vapor generating member is provided with a novel carbon collecting element adapted to be removed for cleaning away carbon deposits. In carrying out this feature of the improvement I provide a valve construction for controlling the discharge from the generator, in which construction the valve operating member is also utilized as a carbon collecting element extending through the vapor generating chamber.

A further feature of novelty resides in the arrangement of the means for operating the vapor discharge valve whereby the adjustment of this valve is accomplished by a movement solely in an axial direction, with a view to avoiding any injury thereto that might follow from a rotary movement of said valve.

Further features of improvement reside in details of the arrangement of the vapor generating and distributing chambers and the vapor passage forming the communicating channel therebetween, as hereinafter described.

It is also sought to provide an extremely simple and compact construction comprising few parts and adapted to be manufactured at small expense.

With these general objects in view the invention will now be described with reference to the accompanying drawing illustrating one form of construction which has been devised for embodying the improvement, after which those features therein deemed to be novel will be set forth and defined in the appended claims.

In the drawing—

Figure 1 is a longitudinal sectional view showing a burner constructed in accordance with the present invention;

Figs. 2 and 3 are plan and end views, respectively, of the same;

Fig. 4 is a transverse section taken on the line 4—4 of Fig. 1; and

Fig. 5 is an enlarged longitudinal sectional view, partly broken away, of the generator tube.

Referring now to the said drawing in detail, this illustrates a burner structure comprising a casting 6 the interior of which forms a vapor distributing chamber 8, the upper portion of said casting being of a curved contour transversely, as represented in Fig. 4, and formed with a plurality of transverse slits 10 for the discharge of the vapor. This vapor is received from a vapor feeding passage 12 formed in a tubular member 14 having an upturned goose-neck outer end 16, the inner end portion of said passage 12 being formed by the horizontal channel-shaped portion of the member 14 in conjunction with the bottom of the chamber 8. The extreme inner end of the passage 12 is provided with a pair of vapor outlet openings 18 as shown in Figs. 1 and 4. The member 14 is secured in place by means of a screw 20 extending through the bottom of the casting 6 and also by means of screws 22 extending through a plate projection 24 formed integral with the member 14 and secured by said screws 22 to one end of the casting 6.

A tubular vapor generating member 26 is supported at one end in said plate projection 24 and at its opposite end in a plate bracket 28 fastened by screws 30 to the corresponding end of the casting 6, the generating member 26 being thus supported in longitudinal position overlying the vapor distributing chamber 8. At the discharge end of said member 26, the same is fitted with a valve nipple 32 located directly opposite the combined vapor and air-mixing opening 34 forming the inlet into the feed passage 12. The valve passage of said nipple 32 is fitted with a needle valve 36 formed on the end of a rod 38 extending axially through the vapor generating chamber formed by the tube 26. The other end of said rod 38 is fitted into a valve operating stem 40 provided with the operating handle or knob 42, said stem being screwed into a gland or nipple 44 which in turn is secured by the pipe sleeve 46 to the tube 26. The gland or nipple 44 also carries a packing washer 110

48 and collar 50 surrounding the valve operating stem 40. The rod 38 extends into an axial recess 51 in the stem 40 and is connected thereto by means of a pin 52 secured 5 to the stem 40 and operating in an annular groove 54 in the end of said rod (see Fig. 5), so that the stem 40 is thus operable to impart longitudinal or axial movement to the rod 38 without any rotation of said rod or 10 of the needle valve 34 connected thereto.

Oil is admitted under pressure from a supply pipe 56 fitted with a valve 58 and communicating with the interior of the sleeve 46.

15 By means of the foregoing construction a burner structure is provided in which the generator tube 26 overlies the vapor distributing slits 10 and the rod 38 extends axially through the vapor generating chamber 20 formed by said tube 26. This rod, being of metal, and a good conductor of heat, acts as an effective collecting element for the deposit of carbon, and the construction shown provides for the convenient removal 25 of this rod as often as required for the cleaning off of any deposits thereon. The said rod also serves the further function of operating the valve 36, and in order that neither the removal of this rod for cleaning 30 purposes nor its operation for regulating the valve may work any injury thereto, such as would follow the grinding contact produced by a rotary movement, the rod 38 is operated solely by an axial movement 35 effected by the rotation of the stem 40 and its rotary or journaled connection with the rod 38. The vapor formed in the generator tube discharges, along with a mixture of air, into the inlet opening 34 of the passage 40 12, whence it flows through the lateral passages 18 and is distributed to the various slits 10 in an obvious manner. The construction is such as to admit of no back-fire at either end of said feed passage 12, and 45 the burner operation of the construction has been found to prove both efficient and economical and particularly free from noise or any disagreeable odors, fumes or smoke.

While I have herein illustrated and described what I now regard as the preferred form of embodiment of the invention, I desire to reserve the right to make all such

formal changes or modifications as may fairly fall within the scope of the appended claims.

55

Having described the invention, what I claim and desire to secure by Letters-Patent is:

1. An oil burner comprising a vapor distributing chamber and a vapor generating member overlying said chamber, said chamber being provided with a vapor passage 60 extending centrally within said chamber, said passage being in communication at one end with said generating member and provided at its other end with lateral vapor discharge passages in communication with said chamber.

2. An oil burner comprising a vapor distributing chamber, a vapor generating tube 70 overlying said chamber, and a tubular goose-neck member providing a vapor passage having a combined air and vapor-mixing inlet opening in spaced relation to one end of said generating tube, said member 75 having a channel-shaped horizontal portion projecting into one end of said chamber and forming with the bottom of said chamber the horizontal portion of said vapor passage, the inner end of said vapor 80 passage having lateral vapor discharge passages communicating with said distributing chamber.

3. An oil burner comprising a vapor distributing chamber, a vapor generating tube 85 overlying said chamber, a tubular goose-neck member providing a vapor passage having a combined air and vapor-mixing inlet opening in spaced relation to one end of said generating tube, said member being 90 detachably secured to one end of said distributing chamber and having a horizontal portion projecting centrally within said chamber and having lateral vapor discharge 95 passages in communication therewith, means for supporting one end of said generating tube at one end of said distributing chamber, and an upwardly extending portion formed integral with said tubular member in supporting relation with the other end of said 100 generating tube opposite said inlet opening.

In witness whereof I hereto affix my signature.

ABRAHAM L. MARSHALL.
